DISPENSING NOZZLE GUARD

Eugene G. Sutcliffe, St. Louis, Mo.

Application March 21, 1955, Serial No. 35,141

Term of patent 14 years

(Cl. D52—2)

Figure 1 is a side elevational view of a dispensing nozzle guard, showing my new design, with a gasoline dispensing nozzle depicted in broken lines for purposes of illustration.

Figure 2 is a front view of the guard.

Figure 3 is a top view of the guard.

Figure 4 is a vertical section taken on the line 4—4 of Figure 1.

I claim:

The ornamental design for a dispensing nozzle guard, substantially as shown and described.
